UNITED STATES PATENT OFFICE

2,392,898

LUMBER SPLICING IMPLEMENT

Hans H. Bakken, Pueblo, Colo.

Application May 24, 1944, Serial No. 537,080

1 Claim. (Cl. 144—297)

This invention relates to improvements in lumber splicers and more specifically, to a set of lumber splicing implements. Since the usual dimensions of lumber are not always available in all the usual lengths, it happens frequently that a builder must buy lumber which is longer than that which he really needs. Consequently, he has to cut off parts of the long pieces of lumber, and these parts are waste. It is more advantageous for the builder, and it is a matter of national interest and importance to buy short pieces of lumber, which are cheaper than long pieces, and to make lumber of the required length by putting short pieces together. Therefore, the objects of my improvement are as follows:

First, the provision of a splicer which is light in weight, primarily flat, and which will form a safe connection between two pieces of lumber.

Second, to afford facilities for properly supporting and pressing toward each other the pieces of lumber which are to be connected to each other in such a manner that a long piece consisting of two or more short pieces of lumber, which are joined together end to end, will be perfectly straight.

In the drawing:

Figure 1 is a side elevation of a preferred embodiment of a detail;

Figure 2 is a bottom plan view of the detail shown in Figure 1;

Figure 3 is side elevation of a modification of the detail of Figures 1 and 2.

Figure 4 is a bottom plan view of the modification shown in Figure 3.

Figure 5 is a plan view of two pieces of lumber spliced together according to the present invention;

Figure 6 is a sectional view on the line 6—6 of Figure 5;

Figure 7 is top plan view of a complete embodiment of my invention;

Figure 8 is a side elevation of the complete embodiment of Figure 7;

Figure 9 is a sectional view on the line 9—9 of Figure 7; and

Figure 10 is a sectional view on the line 10—10 of Figure 7.

Similar numerals refer to similar parts throughout the several views.

The details illustrated in Figures 1 to 6 inclusive, are shown in an enlarged scale.

The ends of the lumber pieces 1 and 2 which are to be connected to each other, are first sawed perfectly square so that they will fit well when they are joined together end to end. Then, the

pieces 1 and 2 are laid on a large plank 3, to which a side panel 4 is secured by means of nails or in any other suitable manner (Figures 7 to 10 inclusive). When the pieces 1 and 2 are brought together so that they form one absolutely straight dimension, they are first connected to each other provisionally, preferably by means of fasteners 5 (Figures 5 and 6) or the like, the fasteners 5 shown in the present instance forming no part of my present invention.

Each splicer consists of a piece of thin sturdy material such as sheet metal, plastic material and the like of L-section as shown in Figures 1 to 4 inclusive. One flange 6 of the L-shaped piece is just long enough to cover the shorter side of the ends of the lumber pieces which are to be joined together end to end, whereas the other flange 7 is so long that it—when bent around the lumber—can cover both longer sides of the ends of the pieces of lumber and the second shorter side as indicated in dash- and dotted lines in Figure 1. Flange 7 can also be so long that it—when bent around the lumber—covers all four sides of the ends of the lumber pieces, as indicated in dash and dotted lines in Figure 3 and in full lines in Figure 6. According to the modification shown in Figures 3 and 4, rows of perforations 8 are provided in flange 7 at those places where flange 7 is to be bent around the edges of the lumber pieces 1 and 2.

The plank 3 is provided with lengthwise adjustable means for pressing the pieces of lumber towards one another end to end while they are being joined together.

I prefer to carry out this feature of my invention in the manner shown in Figures 7 to 10 inclusive, where it will be seen that a cleat 10 is lengthwise slidable on the upper side of the left portion of plank 3 and can be retained after adjustment by means of bolts 11 and thumb screws 12; the bolts 11 are extended through the cleat 10 and through longitudinal slots 14 in plank 3 (Figures 7, 8, and 9). To one edge of the upper side of the right portion of plank 3, I secure an angle iron 15, the vertical flange of which is provided with a row of perforations 16, and the inner side of the opposite portion of the side panel 4 is provided with recesses preferably with ratchet teeth 17 as in the instance shown; a flat spring 18 having a protruding part 19 at one end is adapted to be held between the ratchet portion of the side panel 4 and the angle iron 15, through one of the perforations 16 of which the part 19 can be extended as shown in Figures 7, 8, and 10.

When the pieces of lumber have been joined

together provisionally by means of the fasteners 5 as previously referred to, I place the L-shaped open pieces on the plank 3 so that the long flanges 7 lay between the plank 3 and the ends of the pieces of lumber which are to be spliced together, as shown at the left portion of Figures 7 and 8. I adjust the cleat 10 and the resilient spring 18 in such a manner that the ends of the pieces of lumber are pressed towards one another. The straight top surface of plank 3 and the side panel 4 facilitate the straightening out of the lumber pieces. Then I bend the L-shaped pieces around the joined ends and secure the splices firmly to the lumber by means of nails 20 or the like, which are driven through pre-made holes 21 into the lumber as may be seen at the right portion of Figures 7 and 8 and in Figures 5 and 6.

Having thus described my invention, what I claim and desire to secure by Letters Patent in the United States is:

A lumber splicing implement comprising a

plank having a side panel secured to one of its longitudinal edges, a cleat adjustable lengthwise and attached to the top portion of said plank, a flanged angular member secured to the other longitudinal edge at one end of said plank, said angular member having a row of perforations in its vertical flange, a row of recesses in that portion of said side panel which is opposite to said angular member, and a flat spring having one end adapted to be extended through one of said perforations and its other end adapted to engage an opposite recess in said panel, said plank being adapted to support pieces of lumber while they are being joined together end to end, and said cleat in cooperation with said spring being adapted for pressing said pieces of lumber towards one another end to end while they are being joined by a piece of material, all substantially as described.
